UNITED STATES PATENT OFFICE.

BASTIAAN SLAGBOOM, SANDER SLAGBOOM, AND LUWE SLAGBOOM, OF HAWTHORNE, NEW JERSEY.

REGULATOR.

Application filed January 7, 1927. Serial No. 159,629.

This invention relates to improvements in regulators and has particular reference to an engine regulator.

- The primary object of the invention resides in a regulator for use in connection with either an internal combustion engine or a steam engine to govern the speed of the same when running idle, i. e., should the same be run at 200 R. P. M. while operatively connected with some machine or driven means, and a breakage should occur in the driving belt or like part which might result in a speeding up of the engine, the device will automatically operate to maintain the speed at 200 R. P. M. thereby relieving any injury to the engine which might occur by running the same at an excess speed while disconnected from the machine driven thereby.
- Another object of the invention is the provision of an engine regulator which is automatically controlled by the speed of the engine shaft for retarding the control throttle of the engine should the said shaft rotate at an excess speed for which the regulator may be set.

With these and other objects in view, the invention resides in certain novel construction and combination and arrangement of parts, the essential features of which are hereinafter fully described, are particularly pointed out in the appended claims, and are illustrated in the accompanying drawing, in which:—

- Figure 1 is an elevational view of an internal combustion engine with our improved regulator connected therewith.

Figure 2 is an enlarged vertical longitudinal sectional view through the regulator.

- Figure 3 is a horizontal sectional view on the line 3—3 of Figure 2.

Referring to the drawings by reference characters, the numeral 10 designates our improved regulator in its entirety and which comprises a forked bracket 11 mounted on the casing of an internal combustion engine E. A vertical shaft 12 is journalled in a bearing 13 provided in the lower arm of the bracket and which shaft has a cylinder 14 fixedly connected to its upper end and a bevelled gear 15 fixed to its lower end and which gear meshes with a bevelled gear 16 connected to the engine shaft 17 whereby a rotary motion is imparted to the cylinder

14 from the drive shaft of the engine. A piston head 18 is slidably mounted within the cylinder 14 and rests upon a head of mercury M contained within the cylinder and being at a level to permit of a predetermined amount of vertical movement of the piston head with respect to the top end wall of the cylinder. The piston head 18 has its top face dished to provide a well 19 which communicates with the under face of the piston head by inclined ducts 20 through which the mercury M is adapted to pass when the speed of the motor reaches a predetermined point. A piston rod 21 extends from the piston head 18 through the top end wall of the cylinder 14 and is slidably mounted in a bearing 22 carried by the upper arm of the form of the bracket 11. The top wall of the cylinder is provided with air ducts 23 for relieving the pressure above the piston head during upward vertical movement of the same.

Mounted upon the bracket 11 is a second bracket 24 which supports a cylinder 25 which is smaller in diameter than the cylinder 14 but which is in axial alignment therewith, and which cylinder is provided with a removable plate 26 covering the top end of the same. The upper end of the piston rod 21 passes through the cylinder 25 and out through and above the cover plate 26. The piston rod has an elongated slot 27 provided therein and through which a pin 28 extends, which pin is carried by the cover plate 26 for permitting a predetermined amount of upward movement of the piston rod 21 but which holds the rod against turning movement. Slidably mounted within the cylinder 25 and movable upwardly with the piston rod 21 is a piston 29 and which piston has its side walls spaced from the piston rod 21 to provide a chamber 30 therebetween and which contains a quantity of mercury M', the level of which extends above the piston 29 and into an enlarged chamber 31 at the top of the cylinder. The weight of the mercury M' holds the piston head 18 down upon the head of mercury M and by varying the quantity of mercury within the cylinder 25, it is possible to vary the time at which the regulator will automatically operate. The piston 29 is sealed with respect to the walls of the cylinder 25 by means of a packing gland 32.

For controlling the volume of mercury M' within the cylinder 25, there is provided a horizontally disposed auxiliary cylinder 33 having communication with the enlarged 5 chamber 31 by a duct 34 which enters at the bottom of said chamber. A piston 35 is slidably mounted within the cylinder 33 for varying the distance between the inner end of the piston and the end wall of the cylinder 10 so as to regulate the storing capacity for the mercury M' for controlling the weight of the same upon the piston 29. A packing gland 26 seals the joint between the piston 35 and cylinder 33, and which piston is 15 slideable back and forth within the cylinder by a link 37 which is pivotally connected to one end of an actuating or control lever 38, said lever being pivoted between its ends upon a bracket 39, which bracket is supported from 20 the bracket 24. The free end of the handle serves as a manipulating portion 40 by which the lever may be actuated. The bracket 39 is provided with a graduated dial 25 indicative of R. P. M.'s and when the lever is set to a radial position in register with respective graduations, the same will indicate at which speed the engine regulator will automatically operate. It will be appreciated that when the piston 35 is moved out- 30 ward to enlarge the area between the inner end of the piston and the end wall of the cylinder, the same will drain the cylinder 25 of a certain amount of mercury M' and will permit of the operation of the regulator at 35 a reduced speed than if the entire volume of mercury M' was acting upon the piston head 18.

The top end of the piston rod 21 is connected with a push rod 41 which connects 40 to a bell crank lever 42 by reason of a pin and slot connection 43 and which lever in turn has connection with a connecting rod 44 leading to an actuating arm 45 of the butterfly valve 46 of the carburetor 47 which 45 forms a part of the engine E.

In operation, we shall presume that the engine E is running at a speed of 200 R. P. M. at which time the engine is operatively connected up with some piece of 50 machinery or apparatus to be driven. The lever 38 has of course been set to a position to cause the regulator to operate when the revolutions of the engine shaft exceeds 200 R. P. M. by regulating the load of mercury 55 M' within the cylinder 25. In the event that some driving part of the machine should break such as the driving belt between the engine and the machine, the engine will of course increase in speed due to 60 the fact that it is idle. As the speed increases, the cylinder 14 is rotated at a higher speed which causes the body of mercury M to lift the piston head 18 due to the centrifugal motion as it will be appreciated that 65 the mercury will tend to be forced outward

and upward toward the walls of the cylinder consequently causing the lifting of the piston head 18 against the weight of the body of mercury M' within the cylinder 25. The circulation of the mercury M within the 70 cylinder 14 tends to spread against the under face of the piston head when the centrifugal action reaches a certain point, which relieves any further movement of the piston head, as the same is only adapted to be 75 lifted a slight distance as shown in dotted lines in Figure 2 of the drawings. As the piston head 18 moves upward, the piston rod 21 which carries the piston 29 also moves up causing the raising of the level of the mercury M' within the chamber 31, but the distance between the normal level of the mercury and the top of the cylinder is sufficient to accommodate the rise due to the movement of the piston rod and the top cover 80 plate 26 of the cylinder 25 is provided with air ducts 48 for relieving the air pressure within the enlarged chamber as the mercury rises therein. As the piston rod 21 moves upward, it of course, rocks the bell crank 90 lever 42, pulling upon the connecting rod 44 which actuates the butterfly valve 47 to reduce the flow of gas to the carburetor of the engine which accordingly reduces the 95 speed of the same.

Although we have specifically described the use of the regulator in connection with an internal combustion engine, it will be appreciated that the same may be used with a steam engine and the piston rod 21 operatively connected with the throttle for controlling the speed of the engine.

While we have described what we deem to be the most desirable embodiment of our invention, it is obvious that many of the details may be varied without in any way departing from the spirit of our invention, and we therefore do not limit ourselves to the exact details of construction herein set forth nor to anything less than the whole of our invention limited only by the appended claims.

What is claimed as new is:—

1. An engine regulator comprising a rotatable cylinder adapted to be rotated by the drive shaft of an engine, a quantity of mercury contained within said cylinder, a piston head within said cylinder and supported upon the top of said mercury, a rod extending from said piston head and adapted to be operatively connected with the control device of an engine, and weighted means acting upon said rod to hold said piston head down upon said body of mercury whereby rotation of said cylinder at a predetermined rate of speed will cause said body of mercury to lift said head and rod against said weighted means by reason of the centrifugal action of said mercury, said means including a second cylinder, a piston head carried by said shaft and movable within said second

cylinder, and a body of mercury contained within said second cylinder and acting upon said second piston.

2. An engine regulator comprising a rotatable cylinder adapted to be rotated by the drive shaft of an engine, a quantity of mercury contained within said cylinder, a piston head within said cylinder and supported upon the top of said mercury, a rod extending from said piston head and adapted to be operatively connected with the control device of an engine and weighted means acting upon said rod to hold said piston head down upon said body of mercury whereby rotation of said cylinder at a predetermined rate of speed will cause said body of mercury to lift said head and rod against said weighted means by reason of the centrifugal action of said mercury, said means including a second cylinder, a piston head carried by said shaft and movable within said second cylinder, and a body of mercury contained within said second cylinder and acting upon said second piston head and means for varying the quantity of mercury in said second cylinder.

3. An engine regulator comprising a rotatable cylinder adapted to be rotated by the drive shaft of an engine, a quantity of mer-

cury contained within said cylinder, a piston head within said cylinder and supported upon the top of said mercury, a rod extending from said piston head and adapted to be operatively connected with the control device of an engine and weighted means acting upon said rod to hold said piston head down upon said body of mercury whereby rotation of said cylinder at a predetermined rate of speed will cause said body of mercury to lift said head and rod against said weighted means by reason of the centrifugal action of said mercury, said means including a second cylinder, a piston head carried by said shaft and movable within said second cylinder, and a body of mercury contained within said second cylinder and acting upon said second piston head and means for varying the quantity of mercury in said second cylinder, said means including a compartment in communication with said second cylinder, and a member 50 slidably within said compartment for enlarging or reducing the capacity of the same.

In testimony whereof we hereby affix our signatures.
